TIRE

Eathel L. Duncan, Akron, Ohio, assignor to
The Goodyear Tire & Rubber Company

Filed Dec. 23, 1974, Ser. No. 535,898

Term of patent 14 years

Int. Cl. D12—15

U.S. Cl. D12—146

The figure is a perspective view of a tire showing my new design, it being understood that the tread design is repeated throughout the circumference of the tire, as shown schematically by solid lines, the opposite side being substantially the same as that shown.

I claim:

The ornamental design for a tire, substantially as shown and described.
